UNITED STATES PATENT OFFICE.

HERMAN F. DELMANHORST, OF LOUISVILLE, KENTUCKY.

DIRECTION-INDICATOR. **BEST AVAILABLE COPY**

1,134,595.

Specification of Letters Patent. Patented Apr. 6, 1915.

Application filed April 20, 1914. Serial No. 836,033.

To all whom it may concern:

Be it known that I, HERMAN F. DELMANHORST, a citizen of the United States, residing at the city of Louisville, in the county of Jefferson and State of Kentucky, have invented certain new and useful Improvements in Direction-Indicators, of which the following is a specification.

This invention relates to direction indicators intended to be used in connection with conveyances to indicate the direction in which it is intended that the conveyance shall deviate from the course it is pursuing, with more especial reference to its use in connection with automobiles.

An object is to provide means of imparting to observers advance information of the direction in which a conveyance will deviate from the straight course.

20 A further object is to provide a device of the character described which will be sightly in appearance, which may be readily applied to conveyances of various kinds, which will be economical in construction, 25 easily operated and efficient in service.

With the foregoing and other objects in view the invention consists of the novel construction and arrangement of parts illustrated in the accompanying drawing which 30 forms a part of this application in which is set forth an embodiment of the invention, but it is to be understood, that changes, modifications and variations may be resorted to which come within the scope of the 35 claims appended hereunto.

Referring to the drawings wherein similar reference characters designate like parts in the several views; Figure 1, is an elevation of the invention as applied to an automobile; Fig. 2, a side elevation; Fig. 3, a plan view; Fig. 4, a front elevation; Fig. 5, a central, longitudinal section; Fig. 6, a rear elevation of the front half of the device assembled; Fig. 7, a front elevation of the rear half unassembled.

The device comprises a casing —1— substantially spherical in shape and divided on a vertical median line into a forward portion —2— and a rear portion —3— joined 50 by suitable means such as screws —4—, passing from the exterior through interior lugs —5—, on the rear half, and engaging in lugs —6— on the fore half of the casing. 55 The fore part of the casing has a central aperture —7—, surrounded by an annular flange —8—. A reflector —9— has an an-

nular return —10— forming a bearing which is seated within the flange 8, and is adapted to be oscillated therein. A spring —11—, connected respectively to a lug —12—, on the reflector, and a lug —13—, on the casing, serves to maintain the reflector in a normal position. An annular flange —14—, on the rear of the ring 10, projects beyond the circumference thereof and extends substantially half way around the same, and is adapted, by striking against a lug, or stop —15— to limit the oscillatory movement of the reflector. The flange 14 bears against the rear edge of the flange 8 and limits the outward movement of the reflector, and in conjunction with a ring —16— which fits on the ring 10 and bears against the forward edge of the flange 8, retains the reflector in place in the bearing formed by the flange 8. The ring 16 is held in place on the ring 10 by suitable means, such as a set screw —17—. On the forward end of the ring 16 is an inwardly projecting flange —18— which serves to hold a lens —19— 50 between the same and the reflector. A semaphore arm —20— extends from the ring 16 and normally stands in a vertical position and partakes of motion imparted to the reflector. A bridge bar —21— extends rearwardly from the reflector and has on the rear end thereof a depending arm —22— from which projects a trunnion —23—, in axial alinement with the reflector, and which enters a bearing —24— in the rear half of the casing. A pair of swinging frames —25, 26— are pivotally supported at —27—. 55 These frames lie one on either side of the bridge bar 21 and are held thereagainst by suitable means, such as a spring —28—. Each frame carries a pellucid color screen —25', 26'— adapted to be interposed between a source of light —48— and the rear, open end of the reflector 9. It will be observed that normally the bridge bar holds 60 each of the frames to one side, and clear of the opening in the rear of the reflector so that light may pass uninterrupted through said opening, and that the spring 11 serves to return and hold the reflector, and associated elements in the normal position. The source of light may be of any suitable or desired nature, but I have preferably illustrated an incandescent electric bulb, 65 surmounting a socket plug —29—. As suitable means for connecting the indicator to an automobile, I have shown a clamp adapt-

105

110

ed to be secured about the neck —33— of the radiator, and comprising two members —30, 31— of which one is attached to the rear half 3 of the case in alinement with bearing 24, the other member having an opening —32, in alinement with said bearing. To prepare the neck of the radiator for the reception of the indicator a perforation is made in the front and rear walls thereof and a tube —34— secured therein, the internal diameter of which is the same as that of the opening 32 in the clamp 31. The indicator is then placed in position, pointing directly forward, with the opening 32 in alinement with the tube 34 which passes through the radiator neck. An operating rod —35— is passed through the opening 32 and tube 34 and engaged in the trunnion 23, by suitable means such as a squared end —36—. The rod 35 extends back through the dash and is provided with a flexible joint —37—, which permits of the rod being carried to the steering post and there mounted in a suitable bearing —38— thereon. A handle —39— on the end of the rod 35 provides means whereby motion to the right or left may be communicated through the rod 35 to the reflector and the attached semaphore arm to point said arm in the direction it is intended to turn the car. As the reflector is turned, in either direction, the bridge bar 21 moves from its central position and permits one of the frames, that on the side from which the bar is turning, to drop down and interpose a color screen, red or green, according to a known code, which indicates the direction the vehicle is to turn, being that in which the semaphore arm is pointing.

It is thought that from the foregoing the construction, operation and many advantages of the invention will readily be apparent without more extended description.

Having thus described my invention so that any one skilled in the art pertaining thereto may make and use the same, I claim:—

1. A substantially spherical case having a frontal opening, a cone shaped member 50 rotatably mounted in said opening and extending beyond the case, a retaining ring on the extended portion of said member, a bridge bar extending rearwardly from said member, a trunnion on said bar in axial alinement with said member and bearing in the rear wall of the case, a source of light within the case positioned in axial alinement with said member, color screens, means for moving said screens into axial line before said light, said color screens normally held out of the axial line by said bar and means for turning said member.

2. A case having a frontal opening, a reflector member rotatably mounted in said opening and extending beyond the case, a

bridge bar extending rearwardly from said member, a trunnion on said bar in axial alinement with said member and bearing in the rear wall of the case, a source of light positioned within the case in axial alinement with said member, color screens, means for moving the screens into said axial line between the light and the reflector, said screens being held out of the axial line by said bar, and means for oscillating said member.

3. A case having a frontal opening, a reflector member rotatably mounted in said opening and extending beyond the case, a bridge bar extending rearwardly from said member, a trunnion on said bar in axial alinement with said member and bearing in the rear wall of the case, a source of light positioned within the case in axial alinement with said member, color screens pendent on each side of said bar, means for moving said screens into the axial line, said bar normally holding the screens out of said axial line but permitting one thereof to swing into said line when said member is turned, means for oscillating said member, and means for returning said member to a normal position.

4. A case having a frontal opening, a reflector member having a rear opening rotatably mounted in said opening and extending beyond the case, a retaining ring on the extended portion of said member, a bridge bar extending rearwardly from said member, a trunnion on said bar in axial alinement with said member and bearing in the rear wall of the case, a source of light positioned within the case in axial alinement with said reflector, pendent color screens bearing on each side of said bar, means for moving the screens into the axial line between the light and the reflector, said screens being normally held out of the axial line by said bar, means for oscillating said reflector, and means for returning the reflector to the normal position.

5. In combination, a case having a frontal opening, a lens bearing member rotatably mounted in said opening, a bridge bar extended rearwardly from said member, a trunnion on said bar in axial alinement with said member and bearing in the rear wall of the case, color screens pendent in said case and bearing respectively on each side of said bridge, a source of light positioned within the case in the rear of said screens and in axial alinement with said member, a spring connecting said screens, said bar adapted to permit a color screen to be interposed in said axial line when said bar is turned at an angle, means for oscillating said member and means for maintaining said member in a normal position.

6. A substantially spherical shell having a frontal opening, a lens bearing member

- mounted and relatively rotatable in said opening, said member extended exterior of the shell, a bridge bar extended rearward from said member, a trunnion on said bar 5 in axial alinement with said member and bearing in the rear wall of the shell, means connectible with said trunnion for imparting movement to said member, a source of light positioned within the shell in the axial 10 line of said member, color screens adapted to be interposed in said axial line, but normally withheld therefrom by said bar.
7. A casing, comprising joined semi-spheres, having a frontal opening, a cylindrical member mounted and relatively rotatable in said opening, said member extended exteriorly of the case, a retaining ring on said extended portion, a flange on 15 said member limiting the exterior projection thereof, a stop to limit the relative rotary movement of said member, a spring to hold said member in normal position, a bridge bar reaching rearward from said member, a trunnion on said bar in axial alinement with said member and bearing in the rear wall of the case, means 20 connectible with said trunnion for imparting movement to said member, swinging frames resting on either side of said bar, color screens mounted in said frames and adapted to be brought into the axial line of 25 said member by the movement thereof.
8. A casing comprising joined semi-spheres, having a frontal opening, a cylindrical member mounted and relatively rotatable in said opening, said member extended exteriorly of the case, a retaining ring on said extended portion, a flange on 30 said member limiting the exterior projection thereof, a stop to limit the relative rotation thereof, a source of light positioned within said case and in the rear of said screens.
9. A case having a frontal opening, a cylindrical member mounted and relatively rotatable in said opening, said member extended exteriorly of the case, a retaining ring on said extended portion, means limiting the exterior projection of said member, a stop to limit the relative rotary movement of said member, a spring to hold said member in normal position, a bridge bar reaching rearward from said member, a trunnion on said bar in axial alinement with said member and bearing in the rear wall of the case, means positioned exterior of the case and connectible with said trunnion for imparting movement to said member, swinging frames resting on either side of said bar, a spring connecting said frames, color screens mounted in said frames, said bridge bar adapted to permit a frame to swing into the axial line when said bar is moved from its normal position, and a source of light positioned within said case and in the rear of said screens.
